ATTORNEYS.

UNITED STATES PATENT OFFICE.

AUGUSTUS H. KELLER, OF PHILADELPHIA, PENNSYLVANIA, ASSIGNOR OF ONE-HALF
TO GEORGE HAGEY, OF PHILADELPHIA, PENNSYLVANIA.

BURGLAR ALARM.

Application filed March 21, 1924. Serial No. 700,753.

To all whom it may concern:

Be it known that I, AUGUSTUS H. KELLER, a citizen of the United States, residing at Philadelphia, county of Philadelphia, and 5 State of Pennsylvania, have invented a new and useful Improvement in Burglar Alarms, of which the following is a full, clear, and exact description, reference being had to the accompanying drawings, which form a part 10 of this specification.

The object of my invention is to provide a simple mechanically operable burglar alarm which is attachable to an ordinary window composed of upper and lower sashes 15 sliding in parallel planes and which will be automatically operated whenever there is any relative movement of the two sashes away from a position of closure; that is, whenever the lower sash is raised or the 20 upper sash lowered. Alarms of this character are known in the art, my object being to simplify the construction and also to provide a construction which will produce, when operated, a penetrating sound of a 25 peculiar character.

A preferred embodiment of the invention is shown in the accompanying drawing, in which—

Fig. 1 is an elevation of my alarm applied 30 to a window, looking toward the window.

Fig. 2 is an elevation taken at right angles to Fig. 1, the two window sashes showing in section.

Fig. 3 is a detail side view, partly in section, of the spring-containing rotary box.

Fig. 4 is a detail view, in perspective, of the hub connecting said box and the toothed wheel and on which the cord is wound.

Fig. 5 is a side view of the rotatable 40 toothed wheel.

To a bracket *a* is secured a shaft *b*. Turnable on shaft *b* is a box *c*. Within box *c* is a coil spring *d* one end of which is secured to the box and the other to the shaft. This 45 spring is normally unwound (not under tension). Also turnable on shaft *b* is a toothed wheel *e*. Extending between box *c* and toothed wheel *e* is a hollow hub or sleeve *f* having, at opposite ends, projections *f'* and *f''*. Projections *f'* extend through slots *c'* 50 in one wall of the box and are bent against the inside of the box wall. Projections *f''* extend through slots *e'* in the toothed wheel and are bent against the outside face of the wheel. By these means box *c*, sleeve *f* and

toothed wheel *e* are secured together so as to be turnable in unison.

Secured to bracket *a* is a sound box, the same comprising a hollow body *g* and a hollow, open-ended horn-shaped projection *h*. 60 Secured to the sound box is a flexible finger *i* engaging the toothed periphery of wheel *e*.

Bracket *a* is mounted on the lower sash *x* of a window. Preferably, the upper face of the lower sash is provided with a cleat *k*, 65 and bracket *a* is secured to the sash by sliding the horizontal arm of the bracket under the cleat.

Wound around the sleeve *f* is a cord *j*, one end whereof is secured to the sleeve and the 70 other end to the lower part of the upper sash *y*, as by means of hook *m*.

If the lower sash *x* is raised, or the upper sash *y* lowered, from the positions that the sashes occupy when the window is closed, 75 cord *j* is unwound (winding up spring *d*) and rotates sleeve *f*, thereby rotating wheel *e*. Rotation of wheel *e* causes finger *i* to snap over the teeth of the wheel and produce a clicking sound. This sound is greatly so magnified by reason of the attachment of finger *i* to the sound box. In fact, the sound produced is quite penetrating.

When the lower sash *x* or the upper sash *y* is returned to the position occupied by the 85 sashes when the window is closed, spring *d* unwinds and re-winds cord *j* on sleeve *f*.

Having now fully described my invention, what I claim and desire to protect by Letters Patent is:

1. The combination with the sashes of a window; of a mechanical burglar alarm comprising a bracket secured to one window sash, a toothed wheel turnable on the bracket, a sound box secured to the bracket, 90 a flexible finger secured to the sound box and engageable with the teeth of the wheel, and means connecting said wheel with the other sash and adapted, in the movement of either sash, to turn the wheel and cause said finger 100 to click over the teeth thereof: the sound box comprising a hollow body and a horn open at both ends, one open end of the horn communicating with the hollow interior of the sound box body.

2. The combination with the sashes of a window; of a mechanical burglar alarm comprising a bracket secured to one window sash, a shaft fixed to the bracket, a hollow box and a wheel turnable on the shaft, one 110

wall of the box and the body of the wheel being slotted, a hollow hub enclosing the shaft between the box and wheel, projections on the ends of the hub extending through 5 the slots of the box wall and wheel respectively and bent angularly so as to fixedly connect the box and wheel, a coiled spring within the box one end of which is secured to the box and the other end of which is secured to the shaft, a cord secured to the other sash and wound about the hub, and 10 audible alarm mechanism operable by the wheel in its turning movement.

3. The combination with the sashes of a 15 window, of a mechanical burglar alarm comprising a bracket secured to one of the sashes,

a shaft secured fixedly to the bracket, a wheel and a hollow box turnable on the shaft, a hub between the wheel and box, opposite ends of the hub being secured to said wheel and box, 20 the hub, box and wheel thereby being turnable in unison, a spring within the box, one end fixed to said shaft and the other end secured to the box, a cord wound around said hub and secured to the other sash, and alarm 25 mechanism carried by the bracket and operated by said wheel.

In testimony of which invention, I have hereunto set my hand, at Philadelphia, Pa., on this 18th day of March, 1924.

AUGUSTUS H. KELLER.
